UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

AIR-FEED BRAKE FOR ROCK DRILLS.

Application filed October 12, 1922. Serial No. 593,947.

To all whom it may concern:

Be it known that I, FRED M. SLATER, a citizen of the United States, and a resident of Easton, county of Northampton, and 5 State of Pennsylvania, have invented a certain Air-Feed Brake for Rock Drills, of which the following is a specification, accompanied by drawings.

This invention relates to fluid actuated 10 rock drills, but more particularly to a device for controlling the feeding element of a stope drill, although the invention may be applied to any drill having a fluid actuated feeding element.

15 The invention is illustrated in connection with a stope drill having independent rotation for the drill steel shown in this instance as a rotary motor, and the objects of the invention are to enable the members of the 20 fluid actuated feeding element of a machine of this type, to be positively locked against relative movement or to have the relative movement checked without positively locking the members.

25 Another object of the invention is to effect the control of the braking device by fluid actuated means operating in accordance with the resistance to rotation encountered by the drill steel in operation.

30 The invention is illustrated in the accompanying drawings, in which—

Figure 1 is a longitudinal sectional elevation of a stope drill embodying the invention,

35 Figure 2 is a transverse sectional view of Figure 1 on the line 2—2 looking in the direction of the arrows,

Figure 3 is a transverse sectional view of 40 Figure 1 on the line 3—3 looking in the direction of the arrows,

Figure 4 is a transverse sectional view of Figure 1 on the line 4—4 looking in the direction of the arrows,

45 Figure 5 is a side elevation partly in longitudinal section of a stope drill embodying a modification of the invention, and

Figure 6 is a transverse sectional view through the motor of Figure 5 on the line 6—6 looking in the direction of the arrows.

50 Referring to the drawings, the cylinder A of the rock drill is provided with a reciprocating piston B adapted to impart blows of impact to the anvil block C through which they are transmitted to the shank of the drill steel D. The drill steel extends into

the chuck E in the front head F, which chuck is adapted to be rotated through suitable gears G and H and shaft J from an independent rotation motor, in this instance, shown as a rotary gear motor comprising 60 the gears K and L in the back cylinder extension O.

Motive fluid is admitted to the motor casing through the inlet P and exhausted at the outlet Q in the usual manner for driving 65 the gear motor and imparting rotation to the drill steel D.

The fluid pressure feeding element comprises two relatively movable members and includes the feed cylinder P' and the feed 70 piston Q' having the piston rod R provided with the rock engaging pointer S. The piston rod R non-rotatably engages the cylinder P' and is provided with a groove T engaging the tongue or rib U on the cylinder. 75 The feed cylinder P' is provided with a feed cylinder head V over which is placed the head block W, and the back head X of the machine is interposed between the back cylinder extension O and the head block W. 80 The parts are adapted to be suitably held together by the usual side bolts Y, a portion of one of which is shown in Figure 5.

The braking device includes a longitudinally movable and rotatable brake rod Z 85 having threads a engaging a threaded sleeve b within the piston Q', which sleeve in this instance serves to hold the piston to the piston rod R, as by means of the threads c. Interposed between the head d of the brake 90 rod Z and the feed cylinder head V are two sets of longitudinally movable brake discs, one set of discs e being keyed to the feed cylinder head as by means of the keys or ribs f, and the other set of discs g alternating with the discs e and being keyed to the brake rod Z as by means of the keys or ribs h on the brake rod. The head block W is suitably provided with a partition j forming a pressure chamber k in the head block 100 and a flexible diaphragm o is preferably located in the said pressure chamber over a button or plunger p extending through the partition j and bearing on the head d of the brake rod Z, so that pressure fluid supplied to the pressure chamber k will force the diaphragm o and plunger p downwardly upon the brake rod Z, which forces the brake discs e and g together, thus locking the 105 brake rod Z against rotation or checking its 11

rotation according to the pressure applied.

Pressure fluid is supplied to the machine through the throttle valve q in the back head X controlled by the usual handle r and a passage s leads from the throttle valve through the back head X and head block W and feed cylinder head V for supplying pressure fluid to the feed cylinder P' . When the brake discs are released, the feed cylinder may rise on the feed piston Q' at the same time carrying the brake rod Z upwardly and causing the brake rod to rotate. When the brake rod is locked against rotation or if its rotation is retarded, the feeding element is locked or checked in its movement.

In Figures 1 to 4 inclusive, one form of device is illustrated for automatically controlling the supply of pressure fluid to the pressure chamber k above the diaphragm o automatically in accordance with the resistance to rotation of the drill steel. In said figures, the back head X is provided with a handle t pivoted for transverse movement upon a pivot pin u . The stop v limits the movement of the handle in one direction, and a projection w on the handle is adapted to bear upon the end x of the valve y located in the back head X and controlling the passages 2 and 3 in the back head leading from the throttle valve q to the pressure chamber k above the diaphragm o . A passage k' in the back head X forms a communication between the chamber k and the atmosphere when the valve y is in its inner position. A spring 4 interposed between the valve y and the plug 5 normally holds the valve in the position indicated in Figures 1 and 2, in which the supply of fluid to the chamber k is cut off. Upon sufficient increase of resistance to rotation encountered by the drill steel, the machine will tend to twist or turn backwardly and assuming that the operator has his hand upon the handle t , holding said handle against rotation, it will be obvious that the valve y will be pushed against the projection w on the handle t and the valve will be moved against its spring until the passages 2 and 3 are placed in communication and passage k is cut off, which will admit pressure fluid to the chamber k , depressing the diaphragm o and forcing the head b of the brake rod Z downwardly upon the brake discs, thus carrying the discs into engagement and either locking the brake rod Z against rotation or checking its rotation to apply a braking effect to the feeding element. Upon decrease of resistance to rotation, the spring 4 will return the valve to normal position cutting off the supply of pressure fluid to the chamber k , and pressure fluid from the chamber k will be exhausted to atmosphere through the passage k' .

In Figures 5 and 6 a modification of the

invention is shown, in which supply of pressure fluid to the chamber k above the diaphragm o is automatically controlled by a valve 6 located in the back head 7 and adapted to be actuated by increase of back pressure in the rotation motor, due to increased resistance to rotation encountered by the drill steel D . In this instance, motive fluid is supplied from the throttle valve q through the passage 8 to the inlet P of the motor and a branch passage 9 leads from the inlet of the motor to the valve chamber 10 in front of the enlarged head 11 of the valve. A smaller head 12 of the valve controls the passages 13 and 14 leading from the throttle valve q to the pressure chamber k . The outer face of the smaller valve head 12 is vented to atmosphere through the port 15. The head block W is provided with a rotation handle 16 of the usual form, rigidly connected thereto upon which the operator maintains his hand during the operation. Upon a sufficient increase of resistance to rotation of the drill steel D , the back pressure in the motor casing will increase and will force the valve inwardly, since the pressure on the enlarged head 11 will overcome the differential pressure between the heads 11 and 12 and communication will be established between the passages 13 and 14 so that the diaphragm o will be forced downwardly and the braking effect will be applied to the brake rod Z as described in connection with Figure 1, it being understood that the construction of the brake and the feed cylinder and its parts is the same in Figure 5 as in Figure 1. Upon decrease of back pressure in the gear motor, the differential pressure between the valve heads 11 and 12 will move the valve to normal position and cut off the supply of fluid pressure to the chamber k , and pressure fluid in the chamber k will be exhausted to atmosphere past the smaller head 12 and through the port 15.

I claim:

1. In a fluid actuated rock drill having independent rotation for the drill steel, the combination of a percussive element, a fluid actuated feeding cylinder, a piston slidable in said feeding cylinder and secured against rotation with respect thereto, a back head for the percussive element, a handle pivoted on the back head for resisting rotation of the rock drill, a fluid actuated brake associated with said piston for checking and preventing relative movement between the piston and the feeding cylinder, and a normally closed valve in said back head in constant contact with the handle for controlling the action of the said brake whereby the valve is opened by the handle for admitting pressure fluid to the brake.

2. In a fluid actuated rock drill having independent rotation for the drill steel, the

combination of a percussive element, a fluid actuated feeding cylinder, a piston slideable in said feeding cylinder and secured against rotation with respect thereto, a rock engaging foot piece carried by the piston, a back head for the percussive element, a handle mounted pivotally on said back head for resisting rotation of the rock drill when the steel binds in the drill hole, a rotatable brake rod movable with the feeding cylinder and having threaded engagement with said piston whereby said rod is rotated, a fluid actuated brake for controlling rotation of said rod, a valve in said back head in constant contact with the handle whereby the valve is automatically opened to admit pressure fluid to the brake when the rock drill rotates against resistance applied to the handle, and a spring to hold the valve against the handle.

20 3. In a fluid actuated rock drill having independent rotation for the drill steel, the combination of a percussive element, a fluid actuated feeding cylinder, a piston slideable in said feeding cylinder and secured against

rotation with respect thereto, a rock engaging foot piece carried by the piston, a back head for the percussive element, a handle mounted pivotally on said back head for resisting rotation of the rock drill when the steel binds in the drill hole, a rotatable brake rod movable with the feeding cylinder and having threaded engagement with said piston whereby said rod is rotated, a fluid actuated brake associated with said rod for checking and preventing rotation thereof, a diaphragm between said brake and the back head forming a pressure chamber, a valve in said back head in constant contact with the handle whereby the valve is automatically opened to admit pressure fluid to the pressure chamber for applying the brake when the rock drill rotates against resistance applied to the handle, and a spring for holding the valve in a normally closed position.

In testimony whereof I have signed this 45 specification.

FRED M. SLATER.
